UNITED STATES PATENT OFFICE

BUGGERO RIGHETTO, OF TURIN, ITALY, ASSIGNOR OF ONE-HALF TO SEVERINO TRI-SOGLIO AND ONE-HALF TO LUIGI CASTELLI, BOTH OF TURIN, ITALY

ELECTROMAGNETIC IGNITION DEVICE

Application filed January 23, 1928, Serial No. 248,840, and in Italy January 22, 1927.

My present invention relates to an electro-magnetically operated device adapted to light gas-nozzles, -burners or -stoves, or fuel mixture flames generally, and has for its 5 object to provide a device which will be adapted to be supplied both by direct and alternating current, and which will be of a very compact and cheap construction, and very practical in use.

10 Another object of the invention is to provide a device of the class set forth, which is comprised in but three elements, namely, a fixed core, a vibratory blade, and a substantially fixed blade, in addition to the usual 15 magnitizing coil employed to energize the fixed core, the vibratory blade being the only element which vibrates when the core is energized.

I am aware that devices of the kind referred to have been proposed, but have been, without known exception, provided with a movable core. In the known devices, however, the movable core tends to displace itself in order to bring its center of gravity 25 to the middle of the magnetic field, and the energy of the latter is consumed in causing such displacement and to overcome the comparatively great inertia of the movable core.

My improved device substantially consists 30 of an electro-magnetical vibrator or sparking device, the sparking between the contacts of which is utilized for ignition purposes.

In carrying out the invention, I provide 35 a suitable coil winding, not only to get such number of ampere-turns as will be capable of attracting the vibrating armature, but for the purpose of securing a comparatively low current, in order to avoid damages in 40 the sparking points of the vibrating contacts. For such purpose I provide a very thin coil wire of a comparatively considerable length, so that the wire coil will itself provide for a sufficient resistance when the 45 apparatus is put in a direct current circuit.

If on the contrary the apparatus is put in an alternating current circuit, the impedance of the coil must be added to its own wire resistance, and the apparatus will 50 therefore operate better and last longer.

With the foregoing and other equally important objects and advantages in view, the invention resides in the certain new and useful combination, construction and arrangement of parts as will be hereinafter 55 more fully described, set forth in the appended claims, and illustrated in the accompanying drawing, in which:—

In the drawing:

Fig. 1 is a partial sectional view of said 60 embodiment, while

Fig. 2 is a diagram of the electrical connections.

Referring to the drawing, wherein like characters of reference designate corresponding parts throughout the two views thereof, the embodiment of the invention, as shown therein by way of example, comprises a coil 1 surrounding with a little play a soft iron core 2. While the coil is fixedly carried by 70 the socket 8 of the device, the core on the contrary is axially displaceable and adjustable. For this purpose one end of the core is provided with a threaded rod 3 of brass or like paramagnetic metal, which will be 75 adjusted in position by screwing it in a threaded hole of the cap 7, a milled nut 4 or the like serving as a lock-nut. The socket 8 carries a fixed band or tongue 6, while another band 5 is free to oscillate by being connected by a suitable hinge joint 12 to the socket. At their free ends of the said bands are each provided with a contact or sparking point 14 and 13 respectively, the said 80 points being made of a strong heat resisting metal, such as soft iron, and being so shaped as to be prevented from rapidly becoming worn out. 10 is a breaker arranged on the handle 9 of the device and adapted to close the supply circuit. 85

The iron core is made displaceable so as to be adapted from time to time to compensate for the wear of the sparking points and thereby to keep constant the gap between the core pole and the vibrating band. 90

In the embodiment shown, 11 denotes a spring adapted to press tongue 5 upon the fixed band 6, causing thereby the circuit to be closed even if the device be used in an inverted position, whereby the own weight 100

of the said tongue might not bring it to contact with the band 6. It will however be understood that the said spring is merely shown for explanatory purposes and may have any desired shape.

5 The current leads are passed in a hole 15 within the handle 9 and led to the coil terminals.

10 The operation of the device is self-explanatory, as clearly shown in the diagram of Fig. 2, and requires no further explanation.

I claim:

15 1. An electromagnetic ignition device comprising an exciting coil, a substantially fixed sparking point, an oscillating sparking point adapted to be magnetically actuated by said coil when the latter is energized, and a relatively movable core for varying the magnetic effect of said coil whereby the amplitude of movement of said oscillating sparking point will be adjusted correspondingly with any increase in length of the normal air gap between the latter 20 and said fixed sparking point due to wear thereof during continued use.

20 2. An electromagnetic ignition device comprising an exciting coil, a core axially displaceable within said coil, means supporting said coil, a substantially fixed blade, an oscillating blade adapted to be actuated by the magnetic effect of said core when said coil is energized, sparking points carried by said blades, and means for adjusting said core relative to said oscillating blade, whereby to vary the amplitude of movement thereof correspondingly with any increase in length of the normal air gap between said sparking points by reason of wear of 25 the latter during continued use.

25 3. An electromagnetic ignition device comprising an exciting coil, a core axially displaceable within said coil, means supporting said coil, a substantially fixed blade, an oscillating blade adapted to be actuated by the magnetic effect of said core when said coil is energized, sparking points carried by said blades, and means for adjusting said core relative to said oscillating 30 blade whereby to vary the amplitude of movement thereof correspondingly with any increase in length of the normal air gap between said sparking points by reason of wear of the latter during use, said means 35 also acting to lock said rod and the core in any of the positions of adjustment thereof.

35 4. An electromagnetic ignition device comprising an exciting coil, a core axially displaceable within said coil, a frame enclosing said coil, a rod extending axially from said core, a substantially fixed blade, an oscillating blade adapted to be vibrated by said core when said coil is energized, sparking 40 points carried by said blades, and means

engageable with said frame for adjusting said rod and the core relatively to said oscillating blade whereby to vary the amplitude of movement thereof correspondingly with any increase in length of the normal 70 air gap between said sparking points by reason of wear of the latter during use.

5. An electromagnetic ignition device comprising an exciting coil, a core axially displaceable within said coil, a frame enclosing said coil, a rod extending axially from said core and outwardly of said frame, a substantially fixed blade, an oscillating blade adapted to be vibrated by said core when said coil is energized, sparking points 75 carried by said blades, and means engageable with the outer side of said frame for adjusting said rod and the core relatively to said oscillating blade whereby to vary the amplitude of movement thereof correspondingly with any increase in length of the normal air gap between said sparking points by reason of wear of the latter during use, said means acting to lock said rod and the core in any of the adjusted positions thereof when engaged with the said frame.

6. An electromagnetic ignition device comprising an exciting coil, a core axially displaceable within said coil, a support for 95 said coil, a housing carried by said support and enclosing said coil, a screw threaded rod extending axially from said core and outwardly of said housing, a substantially fixed blade extending from said support, 100 an oscillating blade also extending from said support and adapted to be vibrated by said core when said coil is energized, sparking points carried by said blades, and means carried by the threaded portion of said rod 105 and engageable with said housing for adjusting the rod and core relatively to said oscillating blade whereby to vary the amplitude of movement of the latter correspondingly with any increase in length of the normal air gap between said sparking points by reason of wear of the latter during use.

In witness whereof I have hereunto set my hand.
